PRESSURE FLUID MOTOR

Frank E. Sinclair, Claremont, N. H., assignor to
 Sullivan Machinery Company, a corporation of
 Massachusetts

Application March 1, 1940, Serial No. 321,749

14 Claims. (Cl. 121—19)

This invention relates to pressure fluid motors, and more particularly to improvements in pressure fluid motors of the reciprocating piston, percussive type especially designed for use in hammer rock drills.

An object of this invention is to provide an improved pressure fluid motor having improved fluid distribution means. Another object is to provide an improved fluid distributing valve mechanism for a pressure fluid motor. A further object is to provide an improved pressure fluid motor of the reciprocating piston, percussive type especially designed for use in hammer rock drills. A still further object is to provide an improved fluid distributing valve mechanism of the multi-valve type. Yet another object is to provide an improved valve mechanism embodying a pair of cooperating, relatively movable fluid distributing valves and having embodied therein improved means for effecting movement of the valves into their different operating positions. These and other objects of the invention will, however, hereinafter more fully appear.

In the accompanying drawing there is shown for purposes of illustration one form which the invention may assume in practice.

In this drawing:

Fig. 1 is a view in central longitudinal section taken through a pressure fluid motor constructed in accordance with an illustrative embodiment of the invention.

Figs. 2 and 3 are views similar to Fig. 1, showing the moving motor parts in different operating position.

Fig. 4 is an enlarged fragmentary view taken on the plane of Fig. 1, showing a portion of the improved valve mechanism.

In this illustrative embodiment of the invention the improved pressure fluid motor is shown embodied in a hammer rock drill, although it will be evident that various features of the invention may be embodied in percussive tools of various other types, and in motors adapted for other uses.

The pressure fluid motor disclosed herein comprises a cylinder 1 having a bore 2 containing a reciprocating hammer piston 3. The hammer piston has a piston head 4 slidably fitting the walls of the cylinder bore and a forwardly projecting striking bar 5 adapted to deliver impact blows to the shank of a usual drill steel. The cylinder has a front head 6 closing the front end of the cylinder bore, and the piston striking bar 5 is guided in a bore in this head. The rear end

of the cylinder has an enlarged bore 7 arranged in axial alignment with the cylinder bore, and a rear cylinder head 8 closes the rear end of the cylinder bore and has a circular portion fitting the bore 7 and seated against a shoulder 9 at the front end of the bore 7 in the manner shown. Also arranged in the bore 7 is a rear member 10, a ratchet ring 11 and elements 12 and 13 which cooperate with the rear cylinder head 8 to provide a valve chest. A rear head block 14 suitably secured to the motor cylinder engages the member 10 to hold the elements 10, 11, 12 and 13 in position against the rear cylinder head 8. The elements 8, 10, 11, 12 and 13 are held against rotation within the bore 7 with respect to the cylinder in any suitable manner.

As is usual in hammer rock drills, the drill steel is intermittently rotated as it is percussively actuated by the hammer piston, and the drill steel rotation means includes a rotatable pawl 20 carrier 15 carrying usual spring-pressed pawls engageable with the ratchet teeth 16 of the ratchet ring 11. The pawl carrier has integral therewith a spirally grooved rifle bar 17 which has a sliding interlocking connection with a rifle nut 18 secured within the hammer piston. The rifle bar has a rearward cylindric projection 19 journaled in an axial bore in the rear member 10. The ratchet and pawl mechanism, together with the rifle bar, serves to effect rotary movement of the hammer piston as the latter moves rearwardly during its return stroke, and the rotary piston motion is transmitted to the drill steel through straight grooves 20 on the piston striking bar 5 which cooperate with a usual chuck nut 35 secured to the drill steel chuck in the manner well understood by those skilled in the art. It will thus be seen that when the hammer piston reciprocates to effect percussive actuation of the drill steel, the latter is intermittently rotated.

The fluid distribution valve mechanism may be generally similar to that disclosed in the copending applications to John C. Curtis, Ser. No. 152,609, filed July 8, 1937, and Ser. No. 315,786, filed January 26, 1940, and the present invention constitutes an improvement over the subject matter disclosed in these applications. The element 13 of the valve chest has aligned end bores 21, 21 spaced by an inwardly directed annular partition 22 bounding a reduced bore 23 interconnecting the aligned end bores. The bores 21, 23 receive a pair of cooperating, relatively movable, fluid distributing valves 24 and 25. These valves are movable into abutting relation and have sleeve-like bodies arranged in telescopic sliding

relation and external flanges 28 and 29 respectively slidably fitting the end bores 21, 21. The exterior periphery of the larger sleeve-like body of the front valve 24 slidably fits the bore 23 in the partition, and the exterior periphery of the smaller sleeve-like body of the valve 25 slidably fits the bore in the larger sleeve-like valve body, as clearly shown in Fig. 4. Extending inwardly from the sleeve-like bodies of the valves are internal annular flanges 28 and 29. The rear cylinder head 8 has a sleeve portion 30 extending rearwardly through the valves, and the element 12 has an axial bore within which the rear end of this sleeve portion is tightly fitted. In this instance, the rifle bar 17 is journaled in and extends axially through the bore in the sleeve portion. The internal valve flanges 28 and 29 cooperate respectively with a cylindric projection 31 formed on the exterior of the sleeve portion 30 and a cylindric projection 32 formed on the valve chest element 12, thereby to provide restricted annular spaces 33 and 34 for metering the flow of pressure fluid from a supply chamber 35 within the valves past the valves to the opposite ends of the cylinder bore. Formed in the front face of the valve chest element 12 is an annular recess 36 connected by a port 37 with a distributing passage 38, the latter in turn being connected by a port 39 with the front end of the cylinder bore. Distribution passages 40 in the rear cylinder head 8 connect the front end bore 21 at the front side of the front valve 24 directly with the rear end of the cylinder bore.

The means for supplying pressure fluid to the supply chamber 35 within the valves comprises a throttle valve 43 arranged in a transverse bore in the rear head block 14 and having an internal fluid supply chamber connected by a port 44 with a passage 45 in turn communicating with a chamber 46 in the member 10. Pressure fluid may be conducted from the chamber 46 through a passage 47 and through the ratchet ring 11, through the spaces between the pawl carrier and pawls and the ratchet teeth 16 to a passage 48 communicating with an annular recess 49 in the element 12, this recess in turn connected with an annular passage 50 surrounding the sleeve portion 30 and formed within the cylindric projection 32. The passage 50 communicates directly with the fluid supply chamber 35 within the valves. A throwing passage 51 communicates through a port 52 with the front end bore 21 at the rear side of the front valve flange 28, and this throwing passage is connected by a port 53 with the cylinder bore. An annular exhaust groove 54 is formed in the walls of the cylinder bore substantially midway between the ends thereof and is connected directly to atmosphere throughout an exhaust port 55. The port 52 is connected to a restricted vent port 56 through passages 57 and 58 formed in the elements 12 and 13 respectively. A recess 59 communicates with the distribution passage 38, and a restricted passage 60 connects this recess with the rear end bore 21 at the front side of the external flange 27 of the rear valve 25. A restricted leak passage 61 connects the fluid supply chamber 35 with the rear end of the cylinder bore. Pressure fluid flowing through the port 60 to the front end of the rear end bore 21 at the forward side of the external flange 27 of the rear valve 25 acts on the front pressure area of the external flange so that the opposing pressures on the equal pressure areas at the opposite sides of the external flange are balanced.

The mode of operation of the improved pressure fluid motor is as follows. When the parts are in the position shown in Fig. 1, pressure fluid may flow from the throttle valve 43 through port 44, passage 45, chamber 46, through the spaces surrounded by the ratchet teeth 16 of the ratchet ring, and thence through passage 48, recess 49 and annular passage 50 to the fluid supply chamber 35 within the valves 24 and 25. Pressure fluid may then flow from the supply chamber 35 through the restricted annular space 33, through the front end bore 21 past the front face of the front valve 24, and through distribution passages 40 to the rear end of the cylinder bore at the rear side of the piston head 15 of the motor piston. Concurrently, the front end of the cylinder bore and the end bore 21 at the opposite sides of the external flange 27 of the rear valve 25 are connected to exhaust through the exhaust groove 54. The pressure fluid flowing past the front face of the front valve 24 holds the latter in its rearmost open position with its rear end in abutting engagement with the rear valve 25 and thereby maintains the rear valve in its closed position. Pressure fluid flowing through the passages 40 to the rear end of the cylinder bore acts on the rear pressure area of the piston head to move the motor piston forwardly to effect its working stroke. As the motor piston moves forwardly from the position shown in Fig. 1, the leading edge of the piston head first overruns the port 53 and thereafter overruns the exhaust groove 54, and upon continued forward piston movement the following edge of the piston head uncovers the port 53 of the throwing passage 51, admitting pressure fluid from the rear end of the cylinder bore through port 53, passage 51 and port 52 to the rear end of the front bore 21 at the rear side of the external flange 28 of the front valve 24; and as a result the pressure fluid acts on the effective pressure area of the valve flange to throw immediately the front valve forwardly from the position shown in Fig. 1 to its position shown in Fig. 2. The pressure of the fluid acting on the inner surface of the internal flange 28 of the front valve 24 is somewhat higher than the opposing pressure acting on the outer surface of the flange, due to the restriction at 33, and this higher pressure aids in the throwing of the valve. When the front valve 24 is in its foremost position, it is seated at its front end against the rear face of the rear cylinder head 8 while the rear valve 25 is still momentarily maintained in its rearmost closed position. Accordingly, when the valves are in the position shown in Fig. 2, flow of pressure fluid to the cylinder bore is momentarily completely cut off, and as the motor piston continues to move forwardly by expansion of the fluid and momentum, pressure fluid trapped in the front end of the cylinder bore will be compressed. This compression pressure acts through passage 38 on the effective rear pressure area of the external flange 27 of the rear valve 25, and since the pressure acting on this area will, due to the restricted port 60, build up more rapidly than that acting on the opposing area, the valve 25 will be seasonably thrown forwardly from the position shown in Fig. 2 to its open position shown in Fig. 3. When this valve is thrown forward (opened) it will be held open by the action of live fluid on its full, rearwardly facing area. It will be noted that as the motor piston completes its forward movement, its fol-

lowing edge uncovers the exhaust groove 54 to connect the rear end of the cylinder bore and the front end of the front end bore 21 at the front side of the front valve 24 to exhaust. The 5 motor piston will continue, however, to move forwardly by momentum and will deliver its blow to the drill steel shank. The pressure fluid flowing past the rear face of the rear valve 25, as noted above, holds the latter in its foremost 10 open position, and since its forward end will be in abutting engagement with the front valve, it will thereby maintain the front valve in its closed position. When the rear valve 25 is in the position shown in Fig. 3, pressure fluid will 15 flow from the supply chamber 35, through the restricted clearance space 34, past the rear face of the rear valve 25 and through port 37, distribution passage 38 and port 39 to the front end of the cylinder bore at the front side of the 20 piston head of the motor piston, the pressure fluid acting on the front pressure area of the piston head to move the piston rearwardly to effect its return stroke. As the motor piston moves rearwardly from the position shown in Fig. 3, 25 the pressure fluid in the front end of the cylinder bore expands due to piston movement, so that the pressure in the front end of the cylinder bore and in the distribution passage 38, port 37 and recess 36 is substantially lower than that 30 in the supply chamber 35; and as a result the pressure acting on the inner pressure area of the internal flange 29 and the forward end of the valve body, which pressure is substantially higher than that acting on the rear face of the valve 35 due to the restriction at 34, acts on the rear valve to throw the same, at an appropriate time, rearwardly from the position shown in Fig. 3 to its position shown in Fig. 2. Due to the 40 restricted passage 60, it will be appreciated, the pressure in the front end of the rear end bore 21 at the front side of the external flange of the rear valve will remain substantially higher than the pressure in the distribution passage 38 as the latter pressure falls upon rearward 45 piston movement, and this somewhat higher pressure aids in the rearward throwing of the rear valve. It may be noted, with reference to the restricted passage 60, that its size is of substantial 50 importance since its delaying of the building up of pressure within the space with which it communicates insures rear valve opening, and its retardation of pressure drop in that space is important in determining the time of rear valve closure. As the motor piston continues to 55 move rearwardly by the expansion of the fluid and momentum, the leading edge of the piston head overruns the port 53, and the following edge of the piston head thereafter uncovers the exhaust groove, thereby connecting the front end of the cylinder bore and the rear pressure area of the rear valve to exhaust. It will be 60 evident that the further reduction in pressure in the forward end of the cylinder and in the passage 38 would then, were it not already closed, substantially instantly close the rear valve 25. 65 This is important, for, while during normal drilling closure of the rear valve will precede uncoupling of the exhaust by the front end of the piston head, when the drilling is very heavy due to resistance to rotation, and so rearward piston movement may be slowed down, with diminished pressure drop during the first half or so of rearward piston travel, so that rear valve closure by such a pressure drop may not take place, valve shifting on exhaust opening will still insure 70

motor operation, and power to keep the motor going will be assured by the delay in cut-off for the front end. Upon continued rearward piston movement by momentum, the pressure fluid trapped in the rear end of the cylinder bore is 5 compressed, and this compression pressure acts on the effective front pressure area of the external flange 26 of the front valve 24 to throw the latter rearwardly to its initial position shown in Fig. 1. The sequence of operations above described will be rapidly repeated during normal running of the motor. 10

The restricted vent passages 56, 57 and 58 and the restricted leak passage 61 have no material effect during the normal operation of the motor. 15 However, if the piston should stall in its rearward position in the rear end of the cylinder bore, the pressure fluid leaking through the passage 61 will build up in the rear end of the cylinder bore sufficiently to effect forward piston 20 movement, thereby to effect starting of the motor. When the motor is under substantial load, for instance when the resistance to drill steel rotation becomes abnormally high, the rearward stroke of the motor piston may be shortened, but 25 reciprocation of the piston will still occur, since when the piston head covers the port 53, though it may not move rearward far enough to vent passage 51, still the pressure in the bore 21 at the rear side of the external flange 26 of the 30 front valve 24 will leak to atmosphere through the vent passages, and so the compression pressure built up by the piston head as the rear end of the piston continues to move rearwardly beyond the port 53, will act on the front face of 35 the front valve to throw the latter rearwardly into its open position. Pressure fluid may then flow to the rear end of the cylinder to drive the piston forwardly. It will thus be seen that starting of the motor when stalled is assured and 40 reciprocation of the piston will occur even when the resistance to drill steel rotation becomes abnormally high, though with shortened strokes, thereby preventing stopping of the motor during 45 overload under certain conditions.

As a result of this invention an improved pressure fluid motor is provided having improved fluid distributing valve mechanism. It will further be evident that by the provision of a fluid distributing valve mechanism of the multi-valve 50 type, together with the improved means for effecting movement of the valves into their different operating positions, the structure of the motor is not only simplified but also operating efficiency is increased. Other uses and advantages of the improved pressure fluid motor will 55 be clearly apparent to those skilled in the art.

While there is in this application specifically described one form which the invention may assume in practice, it will be understood that this form of the same is shown for purposes of illustration and that the invention may be modified and embodied in various other forms without departing from its spirit or the scope of the appended claims. 60

What I claim as new and desire to secure by Letters Patent is:

1. In a pressure fluid motor, the combination comprising a cylinder having a bore, a piston reciprocable in said bore, a piston-controlled exhaust for said cylinder bore, a fluid supply, and means for distributing pressure fluid to effect reciprocation of said piston including a valve chest having a valve chamber, a fluid distributing valve in said valve chamber, a fluid distribution pas- 70 75

- 5 sage leading from said valve chamber to said cylinder bore, said valve controlling the communication of said distribution passage with said fluid supply, and means for subjecting said valve to valve throwing pressures for moving said valve into its different operating positions including opposed equal pressure areas on said valve subjected to the pressure in said distribution passage, the communication of both of said areas with said 10 distribution passage being with the latter at points therein short of the cylinder bore and the communication of one of said pressure areas with said distribution passage being relatively restricted.

15 2. In a pressure fluid motor, the combination comprising a cylinder having a bore, a piston reciprocable in said bore, a piston-controlled exhaust for said cylinder bore, a fluid supply, and valve means including a valve chest having a valve chamber, a fluid distributing valve in said valve chamber, a fluid distribution passage leading from said valve chamber to said cylinder bore, said valve controlling the communication of said 20 distribution passage with said fluid supply, and means for subjecting said valve to valve throwing pressures for moving said valve into its different operating positions including opposed equal 25 pressure areas on said valve subjected to the pressure in said distribution passage, the communication of one of said pressure areas with said distribution passage being relatively restricted, and at a point short of the cylinder bore end of said distribution passage, and a pressure area on said valve subjected to the pressure in said fluid supply.

30 3. In a pressure fluid motor, the combination comprising a cylinder having a bore, a piston reciprocable in said bore, a piston-controlled exhaust for said cylinder bore, a fluid supply, and valve means including a valve chest having a valve chamber, a fluid distributing valve in said valve chamber, a fluid distribution passage leading from said valve chamber to said cylinder bore, said valve controlling the communication of said 35 distribution passage with said fluid supply, and means for subjecting said valve to valve throwing pressures for moving said valve into its different operating positions including opposed equal pressure areas on said valve subjected to the pressure in said distribution passage, the communication of both of said pressure areas with said distribution passage being independent of the cylinder bore and the communication of one of said pressure areas with said distribution passage being 40 relatively restricted, and additional opposed pressure areas on said valve respectively subjected to the pressure of said fluid supply and to the pressure in said distribution passage.

45 4. In a pressure fluid motor, the combination comprising a cylinder having a bore, a piston reciprocable in said bore, a piston-controlled exhaust for said cylinder bore, a fluid supply, and valve means including a valve chest having a valve chamber, a fluid distributing valve in said valve chamber, a fluid distribution passage leading from said valve chamber to said cylinder bore, said valve controlling the communication of said 50 distribution passage with said fluid supply, and means for subjecting said valve to valve throwing pressures for moving said valve into its different operating positions including opposed equal pressure areas on said valve subjected to the pressure in said distribution passage.

55 5. In a pressure fluid motor, the combination comprising a cylinder having a bore, a piston reciprocable in said bore, a piston-controlled exhaust for said cylinder bore, a fluid supply, and valve means including a valve chest having a valve chamber, a fluid distributing valve in said valve chamber, a fluid distribution passage leading from said valve chamber to the opposite ends of said cylinder bore, relatively movable fluid distributing valves in said valve chamber for respectively controlling communication of said distribution passages with said fluid supply, and means for subjecting said valves to valve throwing pressures for moving said valves into their different operating positions including opposed pressure areas on said valves adapted to be subjected to valve throwing pressures, one of said valves having equal opposed pressure areas constantly subjected to the pressure in the fluid distribution passage controlled thereby, the communication of one of said equal opposed pressure areas with said distribution passage being relatively restricted.

60 6. In a pressure fluid motor, the combination comprising a cylinder having a bore, a piston reciprocable in said bore, a piston-controlled exhaust for said cylinder bore, a fluid supply, and valve means including a valve chest having a valve chamber, a fluid distributing valve in said valve chamber, a fluid distribution passage leading from said valve chamber to the opposite ends of said cylinder bore, relatively movable fluid distributing valves in said valve chamber for respectively controlling communication of said distribution passages with said fluid supply, and means for subjecting said valves to valve throwing pressures for moving said valves into their different operating positions including opposed pressure areas on said valves adapted to be subjected to valve throwing pressures, one of said valves having equal opposed pressure areas constantly subjected to the pressure in the fluid distribution passage controlled thereby, the communication of one of said equal opposed pressure areas with said distribution passage being relatively restricted, and other opposed pressure areas on said latter valve, one constantly subjected to the pressure in the fluid supply and the other communicable with said latter distribution passage.

65 7. In a pressure fluid motor, the combination comprising a cylinder having a bore, a piston reciprocable in said bore, a piston-controlled exhaust for said cylinder bore, a fluid supply, and valve means including a valve chest having a valve chamber, a fluid distributing valve in said valve chamber, a fluid distribution passage leading from said valve chamber to the opposite ends of said cylinder bore, relatively movable fluid distributing valves in said valve chamber for respectively controlling communication of said distribution passages with said fluid supply, and means for subjecting said valves to valve throwing pressures for moving said valves into their different operating positions including opposed pressure areas on said valves adapted to be subjected to valve throwing pressures, one of said valves having equal opposed pressure areas constantly subjected to the pressure in the fluid distribution passage controlled thereby, the communication of one of said equal opposed pressure areas with said distribution passage being relatively restricted, other op-

posed pressure areas on said latter valve, one constantly subjected to the pressure in the fluid supply and the other communicable with said latter distribution passage, and means providing a restricted communication between said last mentioned opposed pressure areas.

8. In a pressure fluid motor, the combination comprising a cylinder having a bore, a piston reciprocable in said cylinder bore, a piston-controlled exhaust for said cylinder bore, a fluid supply, a valve chest having a valve chamber, fluid distribution passages leading from said valve chamber to the opposite ends of said cylinder bore, relatively movable fluid distributing valves in said valve chamber for respectively controlling communication of said distribution passages with said fluid supply, and means for subjecting said valves to valve throwing pressures for moving said valves into their different operating positions including opposed pressure areas on said valves adapted to be subjected to valve throwing pressures, one of said valves having equal opposed pressure areas constantly subjected to the pressure in the fluid distribution passage controlled thereby and further having other opposed pressure areas, one constantly subjected to the pressure in the fluid supply and the other communicable with said latter distribution passage, the communication of one of said equal opposed pressure areas with said distribution passage being relatively restricted, whereby a drop in pressure in said last mentioned distribution passage, due to expansion of fluid, causes the pressure within said fluid supply acting on said pressure area subjected to the pressure in said fluid supply to effect throwing of said valve.

9. In a pressure fluid motor, the combination comprising a cylinder having a bore, a piston-reciprocable in said cylinder bore, and fluid distribution means for said cylinder including a valve chest having a valve chamber, a pressure fluid supply, a pair of cooperating, relatively movable, fluid distributing valves in said valve chamber, distribution passages leading from the opposite ends of said valve chamber respectively to the opposite ends of said cylinder bore, said valves respectively controlling communication of said distribution passages with said fluid supply, and means for subjecting said valves to valve throwing pressures for moving said valves into their different operating positions including pressure areas on said valves subjected to the pressure in said fluid supply and opposed pressure areas subjected to the pressure in said distribution passages, means on said valves cooperating with elements of said valve chest for providing restricted communication between said fluid supply and said distribution passages, a passage communicating with the cylinder bore and controlled by said piston for subjecting a pressure area on one of said valves to a valve throwing pressure, and a passage for connecting said fluid distribution passage controlled by said other valve with a pressure area on said latter valve, independently of the cylinder bore, so that opposed equal pressure areas on said latter valve are balanced.

10. In a pressure fluid motor, the combination comprising a cylinder having a bore, a piston reciprocable in said cylinder bore, and fluid distribution means for said cylinder including a valve chest having a valve chamber, a pressure fluid supply, a pair of cooperating, relatively movable, fluid distributing valves in said valve chamber, distribution passages leading from the opposite ends of said valve chamber respectively

to the opposite ends of said cylinder bore, said valves respectively controlling communication of said distribution passages with said fluid supply, and means for subjecting said valves to valve throwing pressures for moving said valves into their different operating positions including pressure areas on said valves subjected to the pressure in said fluid supply and opposed pressure areas subjected to the pressure in said distribution passages, means on said valves cooperating with elements of said valve chest for providing restricted communication between said fluid supply and said distribution passages, a passage communicating with the cylinder bore and controlled by said piston for subjecting a pressure area on one of said valves to a valve throwing pressure, a passage for connecting said fluid distribution passage controlled by said other valve with a pressure area on said latter valve so that opposed equal pressure areas on said latter valve are balanced, and vent passage means for providing a continuous restricted vent between said second mentioned passage and the atmosphere.

11. In a pressure fluid motor, the combination of a cylinder having a bore, a piston reciprocable in said cylinder bore, a piston-controlled exhaust for said cylinder bore, a fluid supply, and valve means including a valve chest having a valve chamber, a fluid distributing valve in said valve chamber, a fluid distribution passage leading from said valve chamber to said cylinder bore, said valve controlling communication of said distribution passage with said fluid supply, and means for subjecting said valve to valve throwing pressures for moving said valve into its different operating positions including opposed equal pressure areas on said valve, one of said pressure areas communicating directly with said distribution passage, and a restricted passage connecting said other pressure area with said distribution passage at a point short of the latter's communication with the cylinder bore.

12. In a pressure fluid motor, the combination of a cylinder having a bore, a piston reciprocable in said cylinder bore, a piston-controlled exhaust for said cylinder bore, a fluid supply, and valve means including a valve chest having a valve chamber, a fluid distributing valve in said valve chamber, a fluid distribution passage leading from said valve chamber to said cylinder bore, said valve controlling communication of said distribution passage with said fluid supply, and means for subjecting said valve to valve throwing pressures for moving said valve into its different operating positions including opposed equal pressure areas on said valve, one of said pressure areas communicating directly with said distribution passage, a restricted passage connecting said other pressure area with said distribution passage independently of the cylinder bore, and additional opposed pressure areas on said valve respectively subjected to the pressure of said fluid supply and to the pressure in said distribution passage.

13. In a pressure fluid motor, the combination of a cylinder having a bore, a piston reciprocable in said cylinder bore, a piston-controlled exhaust for said cylinder bore, a fluid supply, and valve means including a valve chest having a valve chamber, a fluid distributing valve in said valve chamber, a fluid distribution passage leading from said valve chamber to said cylinder bore, said valve controlling communication of said distribution passage with said fluid supply, and means for

subjecting said valve to valve throwing pressures for moving said valve into its different operating positions including opposed equal pressure areas on said valve, one of said pressure areas communicating directly with said distribution passage, a restricted passage connecting said other pressure area with said distribution passage independently of the cylinder bore, additional opposed pressure areas on said valve respectively 10 subjected to the pressure of said fluid supply and to the pressure in said distribution passage, and means providing a restricted communication between said last mentioned pressure areas whereby the flow of pressure fluid from said fluid supply 15 to said distribution passage is restricted.

14. In a pressure fluid motor, the combination of a cylinder having a bore, a piston reciprocable

in said cylinder bore, a piston controlled exhaust for said cylinder bore, and motive fluid distribution means for said cylinder including a valve, a fluid conducting passage leading to one end of the cylinder bore, and means for effecting valve 5 throwing to interrupt supply to said passage when the piston uncovers said exhaust during heavy drilling and earlier during normal drilling including means for creating an effective valve throwing differential pressure prior to release for said cylinder end during normal motor operation, said last mentioned means including passage means for connecting an area on said valve with said fluid conducting passage, said passage means opening into said fluid conducting passage at a point be- 10 15 tween the ends of the latter.

FRANK E. SINCLAIR.
